UNITED STATES PATENT OFFICE.

STEPHEN BENNETT, OF BUFFALO, NEW YORK.

HYDROCARBON-BURNER.

SPECIFICATION forming part of Letters Patent No. 408,284, dated August 6, 1889.

Application filed October 29, 1888. Serial No. 289,369. (No model.)

To all whom it may concern:

Be it known that I, STEPHEN BENNETT, of Buffalo, in the county of Erie and State of New York, have invented certain new and 5 useful Improvements in Hydrocarbon-Burners; and I do hereby declare that the following description of my said invention, taken in connection with the accompanying sheet of drawings, forms a full, clear, and exact 10 specification, which will enable others skilled in the art to which it appertains to make and use the same.

My present invention has general reference to hydrocarbon-burners; and it consists, essentially, in the novel and peculiar combination of parts and details of construction, as hereinafter first fully set forth and described, and then pointed out in the claims.

In the drawings already referred to, which 20 serve to illustrate my said invention more fully, Figure 1 is a front elevation of my improved hydrocarbon-burner, part of a stove or other suitable furnace and the steam-expansion chamber being shown in section. 25 Fig. 2 is a plan of the same, one of the generators being shown in a horizontal section to exhibit the interior construction. Fig. 3 is a plan of the burner below the generators, the cover of the steam-expansion chamber being 30 removed. Fig. 4 is a plan of the steam-expansion chamber, and Fig. 5 is a plan of the regulating-valve. Fig. 6 is a transverse sectional elevation in line $\alpha\alpha$ of Fig. 2.

Like parts are designated by corresponding 35 letters of reference in all the figures.

The object of my present invention is the production of an efficient hydrocarbon-burner for heating purposes.

A B are two cylindrical vessels, preferably 40 constructed of wrought-iron pipe, having caps a to close the ends of said pipe. These vessels are generators, A being the oil and B the steam generator.

C is a reservoir constructed to receive the 45 liquids, it having a partition α to separate the oil-chamber C' from the water-chamber D, and it has two glass gages D' D' to show the height of the contents of said reservoir. Two 50 separate vessels may be used, however, if found desirable. From the reservoir C' leads a pipe E, having an adjustable stop-cock F

and a pipe e, to the generator A, while from the receptacle D leads a similar pipe G, having a stop-cock F' and pipe g, to the steam-generator B. The generators are placed in 55 bearings h' , Fig. 3, in a frame having standards H secured together by a tie-rod h , as clearly shown in Fig. 3.

From the generator A leads a pipe I downward, said pipe terminating in a T i, having 60 branch pipes L' L, provided with upwardly-pointing discharge-orifices l, through which the vapor generated in the vessel A issues in a fine stream. From the generator B leads a pipe J downward similar to the pipe of the 65 generator A, said pipe having a T i', two branches V V, elbows j j, and two nozzles k k, said pipe and fittings conveying the steam produced in the chamber B down into a steam-expansion chamber M, consisting of a rectangular pan having a cover N, provided with a removable lid N', there being in the cover 70 an aperture n' for the passage of the pipe I and openings n n, serving as escape-openings for the gases.

Within the generator B is located a pipe P, having upwardly-pointing orifices S, said pipe being surrounded by a tube R, of asbestos fiber covered with wire-cloth O, as shown in 75 Fig. 2.

The regulating-valve consists of a properly-constructed stop-cock having on its spindle f' a lever b, secured with a set-screw c or other similar means. To the valve is attached a stop d, adjustably secured to the coupling f 85 by means of a set-screw d', all as clearly shown in Fig. 5.

In operation the lid N' of the cover N is removed from the steam-expansion chamber and an ignited fuel-cartridge (not shown) 90 placed into the said chamber against the pipe I. The heat thereby imparted to the generator A will soon suffice to evaporate the oil admitted to said generator, the vapor passing downward through the pipes I and L L' and issuing from the orifices n n in the cover of the steam-expansion chamber M. As soon as this takes place, the fuel-cartridge is removed and the lid N' of the cover N replaced, when the heat of the burning vapor will begin to heat the 95 steam-generator B, so that water admitted to the generator will be converted into steam 100

and pass through the pipes J V V' and nozzles *k k* into the steam-expansion chamber M. Here the steam expands and is reduced to the pressure of the atmosphere and the temperature of boiling water. The issuing vapors from the orifices *l* cause an upward current in the expansion-chamber M, and will take up as much of the steam as is required to produce perfect combustion and burn with an intensely-hot flame. Heretofore burners have been constructed in which the steam and vapor commingle in a chamber prior to their escaping from the escape-openings, or the gases have been mixed in the orifices, the steam and vapor escaping with a speed due to the pressure in the generators. This construction is imperfect, for the reason that the steam will in most cases extinguish the burning vapor, and thereby cause serious troubles. This objection is entirely overcome in my burner, where the gases mix only at the point of escape from the expansion-chamber, and where the steam is never hotter or higher in pressure than the pressure of the atmosphere and the temperature due to this pressure. The steam-generator soon becomes red-hot, and the water passing into the same through the orifices S is absorbed by the asbestos tubing R, where it evaporates and passes into the annular space T to be superheated by the heat of the metallic wall of the generator, after which the gases pass through the pipe J, &c., as heretofore described.

In hydrocarbon-burners employing a steam-generator not provided with an absorbent material there arises a serious difficulty, viz: The water entering the generator is held in globular form until at once it is evaporated and explodes. This sudden conversion causes pulsations of the flame and results almost invariably in the blowing out of the flame, and, if unnoticed, results in more or less serious accidents. This is entirely avoided in my burner, the water not reaching the hot metallic shell of the generator in liquid form, but is absorbed by the fibrous asbestos sheet of which the tube R is composed and evaporated before it can reach the said metallic shell.

The regulating-valve is so adjusted that when the lever *b* reaches the stop *d* the proper supply of water and oil passes through the

pipes, such stop, however, not preventing the valves from being entirely closed when desired. This stop arrangement is a desirable feature in valves used for the purpose described. Changes can be readily made by unscrewing the set-screw *c* on the lever *b* and by turning the latter upon the valve-spindle *f* until proper adjustment is reached.

Having thus fully described my invention, I claim as new and desire to secure to me by Letters Patent of the United States—

1. In hydrocarbon-burners, the combination, with the standard H, of the two cylindrical generators A B, having caps and pipes to support them in bearings in said standards, the steam and vapor pipes leading to and from said generators, and the steam-expansion chamber, the latter having the removable cover and lid provided with apertures for the escaping gases, in the manner as and for the purpose stated.

2. The combination, with the standard H, having the tie-rod *h*, of the generators A A, having caps and pipes to support them between said standards, the pipe J, T *i'*, pipes V V, elbows *j*, and nozzles *k*, terminating within the steam-expansion chamber M, the latter being provided with a removable cover having detachable lid and escape-openings *n*, the pipe I, T *i*, and pipes L, having upwardly-projecting discharge-apertures *l l*, the whole being combined and constructed in the manner as and for the object stated.

3. In hydrocarbon-burners, the steam-expansion chamber M, having two apertures in its side for the passage of the nozzles *k k*, the removable cover N, provided with an excision for the passage of the pipe I and further excisions *n*, and the detachable lid N' in said cover, said lid having excisions corresponding with those in the cover, the whole being combined with suitable generators, in the manner as and for the purpose set forth.

In testimony that I claim the foregoing as my invention I have hereto set my hand in the presence of two subscribing witnesses,

STEPHEN BENNETT.
